FOREIGN PATENT DOCUMENTS

CN 202492576 U 10/2012

Primary Examiner — Stella Reid*Assistant Examiner* — Khawaja Anwar(74) *Attorney, Agent, or Firm* — Lerner, David, Littenberg, Krumholz & Mentlik, LLP(57) **CLAIM**

The ornamental design for a keyed spindle, as shown and described.

DESCRIPTION

FIG. 1 is a top perspective view of a keyed spindle showing our new design;

FIG. 2 is a right side view thereof; the left side view being a mirror image thereto;

FIG. 3 is a front view thereof;

FIG. 4 is a rear view thereof;

FIG. 5 is a top plan view thereof; and,

FIG. 6 is a bottom plan view thereof.

The broken lines in the drawings show unclaimed subject matter only and form no part of the claimed design.
